UNITED STATES PATENT OFFICE.

LEONARD MARSH, OF BURLINGTON, VERMONT.

IMPROVEMENT IN SCREWS.

Specification forming part of Letters Patent No. 33,167, dated October 15, 1861.

To all whom it may concern:

Be it known that I, LEONARD MARSH, of Burlington, in the State of Vermont, have invented a new and useful Improvement in the Construction of Screws; and I do hereby declare the following to be a correct description of the same, reference being had to the accompanying drawings, in which—

Figure 1 is a view of one of my improved screws. Fig. 2 shows such a screw inserted in a matrix C, and Fig. 3 represents a modification of the invention applicable to screws of the larger sizes.

The object of the invention is to fix the screw more firmly in its matrix so that it will not be apt to turn by the application of a slight force, nor become loose in consequence of the wear of the matrix—a point of importance in many cases in which screws are applied, but of obvious and paramount consequence in many machines and in some instruments of precision, such as those used for mathematical, philosophical, and astronomical purposes.

The nature of the invention consists in splitting the screw in one or more places in a line parallel to its length, and then imparting an arched form to the split portion. A screw thus constructed when inserted in a matrix is compressed until the flexure of its arched sides is overcome; but the elastic reaction of the bent metal acts like a wedge to hold the screw fixed, so that no ordinary motion, jar, or handling will cause it to start back or get loose and so produce derangement or injury or interfere with precision and accuracy of movement.

In the drawings, Figure 1 represents a screw A, split up the middle for a part of its length, and the split portion B so bent as to form a double arch. The arched form is imparted

by opening the split ends and inserting a rod or mandrel of the proper size and form to give the degree of flexure and elasticity required, and bending the sides over said mandrel until their ends come together, as represented. The rod is then withdrawn. The length of the slit and the curvature of the arch may vary with the size and length of the screw. When the screw is very short it may be split nearly the whole length, and in that case the split should be made at right angles to the nick in the head of the screw.

When the screw is large the slit may be on one side of the center, or on both sides, as shown in Fig. 3, and the strips B B' arched, as before described. In this case the arches must be compressed on inserting the screw, so as to make the threads correspond.

Where a very strong adhesion between the screw and its matrix is required it may be further increased to any degree by inserting in the slit of the screw a strip of some compressible and elastic substance, as soft wood, very narrow, and of a thickness proportioned to the effect desired.

Having thus fully described my invention, what I claim, and desire to secure by Letters Patent, is—

The method hereinbefore described of increasing the adhesion between a screw and its matrix by splitting the screw and forming the split portion into an elastic arch, substantially in the manner and for the purposes set forth.

The above specification signed and witnessed this 20th day of April, A. D. 1861.

LEONARD MARSH.
